(57) **CLAIM**

The ornamental design for an emergency light, as shown and described.

DESCRIPTION

FIG. 1 is a perspective view showing the front, left side and top;

FIG. 2 is a rear view thereof;

FIG. 3 is a front view thereof;

FIG. 4 is a left view thereof;

FIG. 5 is a right view thereof;

FIG. 6 is a top view thereof;

FIG. 7 is a bottom view thereof; and,

FIG. 8 is a perspective view showing the using reference. In the drawings, the broken lines depict environmental subject matter only and form no part of the claimed design.
